UNITED STATES PATENT OFFICE.

WRIGHT DURYEA, OF GLEN COVE, NEW YORK.

MACHINE FOR DRYING STARCH REFUSE AND OTHER SUBSTANCES.

SPECIFICATION forming part of Letters Patent No. 251,847, dated January 3, 1882.

Application filed December 29, 1880. (No model.)

To all whom it may concern:

Be it known that I, WRIGHT DURYEA, of Glen Cove, in the county of Queens and State of New York, have invented certain new and useful Improvements in Machines for Drying Starch Refuse and other Substances, of which the following is a specification.

Although my invention may be applicable to machines for drying various vegetable substances, it is particularly intended for drying the wet refuse from starch-factories. This refuse has heretofore been sold by starch-manufacturers at a very low price because of the necessity of getting rid of it before its souring; and the object of my invention is to provide a machine which may be used advantageously for drying this substance, thus enabling it to be stored for some time without danger of souring or fermentation and disposed of to better advantage.

To this end my invention consists essentially in the combination, in a drying-machine, of an upright trunk or cylinder divided at different heights by hollow floors, pipes for supplying a heating agent to said floors, an upright hollow rotary shaft, blades or scrapers rotating with said shaft above said floors for distributing material upon said floors and discharging it through openings in said floors, perforated pipes projecting radially from said shaft above said floors, and means for forcing air through said shaft and pipes.

The invention also consists in the combination of the upright trunk or cylinder having hollow floors with discharge-openings through them, the upright hollow rotary shaft and radial perforated pipes projecting therefrom above each floor, and means for forcing air through said shaft and pipes.

The invention also consists in various combinations of parts and details of construction, hereinafter described, whereby the effectiveness of the machine is increased, including the combination, with the aforesaid hollow shaft, of "hopper-boys" for distributing material upon the floors of the trunk or cylinder above described, composed of perforated pipes projecting from said shaft and blades or scrapers attached to said pipes.

In the accompanying drawings, Figure 1 represents a central vertical section of a machine

embodying my invention. Fig. 2 represents a similar section at right angles to Fig. 1. Fig. 3 represents a horizontal section upon the dotted line x x , Fig. 1; and Fig. 4 represents a central vertical section of a portion of the upright shaft and a hopper-boy upon a somewhat larger scale.

Similar letters of reference designate corresponding parts in all the figures.

A designates an upright trunk or cylinder closed at the top and divided at different heights by horizontal floors B B' , which are made hollow, and to which steam, hot air, or other heating agent, but preferably steam, is introduced by means of inlet-pipes a , and from which said steam is exhausted through outlet-pipes b . The said two hollow heated floors form two compartments or chambers; but the trunk or cylinder may be of any suitable height and divided by any number of floors, to suit the character of the substance to be dried.

C designates a hopper at the top of the trunk or cylinder A , through which the substance to be dried is introduced, and by which said substance is delivered at or near the center of the upper hollow heated floor, B , and the upper and lower floors, B B' , are each provided with one or more delivery openings or chutes, c , through which the substance in process of drying is successively delivered. From the lower floor, B' , the substance in process of drying is delivered through the opening c into a third compartment, D , provided with a steam-jacket, D' , upon the side and bottom, and said steam-jacket is supplied with steam by a branch, a' , from the inlet-pipe a , and is exhausted of steam by a branch, b' , communicating with the outlet-pipe b .

E designates an upright shaft arranged centrally within the trunk or cylinder A , and supported in a bearing, d , in the top head thereof and in a step-bearing, e , at the bottom. Rotary motion is imparted to this shaft by any suitable mechanism, in the present instance by a counter-shaft, F , mounted in bearings on the top of the trunk or cylinder and driven by means of a belt over a pulley, F' . The shafts E and F are connected by bevel-gear wheels f f' , and through the said wheels the shaft F imparts its motion to the shaft E .

To the shaft E , above the hollow floors B B' ,

are fixed hopper-boys G G', by which the material on each floor is delivered through the opening *c* therein and discharged into the compartment or chamber below. The hopper-boys 5 G G' are each composed of four pipes, *g*, fixed radially in the shaft E, and having extending downwardly from them blades or scrapers *h*, which scrape upon the floor and throw the substance upon the floor outward from the 10 center. As most clearly represented in Fig. 3, the blades *h* are not continuously straight, but are cut transversely, and the outer ends of the portions thus formed are all deflected or bent inward beyond the inner ends of the following 15 portions. This construction provides for each portion of each blade throwing the substance upon the floor outward a distance equal to its length, and then leaving the substance to be taken up by the next blade. The substance 20 being dried is thereby left in contact with the floor for a longer time and becomes more thoroughly dried than if discharged at once.

The shaft E, as clearly shown, is hollow, and in the lower portion thereof below the 25 compartment D are perforations *i*, through which air may pass upward through said shaft and the pipes *g* of the hopper-boys and out into the compartments above the floors B B', through perforations *j* in the lower sides of 30 said pipes. The supply of air forced upward through said shaft may be produced by a fan-blower, H, or other desirable means, and may be exhausted from the chambers or compartments through openings *s* in the side of the 35 trunk or cylinder.

As above stated, the delivery-openings *c* through the floors B B' are near the circumference of the trunk or cylinder A, and in order to deliver the partly-dried substance discharged through said opening in the floor B at a point near the middle of the floor B', I 40 may employ a screw-conveyer, I, arranged in a casing below the floor B, and taking the substance delivered to it through the opening *c*, and delivering it at its inner end near the shaft E. The screw-conveyer I is rotated by bevel-gears *k* from a shaft, J, which is arranged vertically upon the exterior of the trunk or cylinder A, and itself derives motion 45 from the shaft F by means of bevel-gear wheels *l*. A second conveyer similar to I might be arranged below the floor B'; but in lieu of these conveyers a hopper might deliver the substance from the circumference of one floor 50 to the center of the floor next below it.

In the bottom of the compartment D, near its circumference, are delivery chutes or pipes K, (best seen in Fig. 2,) and upon the shaft E, above the bottom of said compartment, is a 55 third hopper-boy, G², comprising perforated pipes *g* and blades *h*, by which the substance, now thoroughly dried, is thrown outward to the delivery chutes or pipes K.

The substance to be dried is introduced 60 through the hopper C in a wet or moist condition, and, falling upon the hollow heated

floor B, is by the hopper-boy G spread over the floor in a thin layer, and gradually and slowly moved outward from the center and delivered through the opening *c* to the conveyer 70 I. By said conveyer the partly-dried substance is delivered near the center of the floor B' and further dried, it being gradually moved outward and discharged through the opening *c* into the steam-jacketed compartment D, from 75 which it is finally delivered through the chutes or pipes K thoroughly dried and fit to be stored for a longer or shorter period without danger of heating or fermentation.

The hopper-boys, instead of having their arms formed by the pipes *g*, as shown in the drawings and hereinabove described, may be made separate from the said pipes and placed between the said pipes, being attached either to the said pipes or to the shaft E in such manner that they may be free to rise and fall automatically, as may be desirable, while they rotate with the shaft and operate to convey the material in process of drying from the center to the skirt of the chambers.

What I claim as my invention, and desire to secure by Letters Patent, is—

1. The combination, in a drying-machine, of an upright trunk or cylinder divided at different heights by hollow floors, pipes for supplying a heating agent to said hollow floors, an upright hollow rotary shaft, blades or scrapers rotating with said shaft above said floors for distributing material upon said floors and for discharging it through openings in said floors, perforated pipes projecting radially from said shaft above said floors, and means for forcing air through said shaft and pipes, substantially as and for the purpose specified.

2. The combination, in a drying-machine, of an upright trunk or cylinder, divided at different heights by hollow floors having in them discharge-openings, an upright hollow shaft, perforated pipes projecting radially from said shaft, above each floor, and means for forcing air through said shaft, and perforated pipes, whereby by the chambers between said floors may be filled with hot air, substantially as and for the purpose specified.

3. The combination, in a drying-machine, of an upright trunk or cylinder divided at different heights by floors having in them discharge-openings, an upright hollow rotary shaft, hopper-boys above each floor composed of perforated pipes projecting from said shaft, and blades or scrapers attached to said pipes, and means for forcing air through said shaft and pipes, substantially as and for the purpose specified.

4. The combination, in a drying-machine, of an upright trunk or cylinder divided at different heights by hollow floors having in them discharge-openings, pipes for supplying a heating agent to said hollow floors, an upright hollow rotary shaft, and pipes projecting therefrom for supplying air between said floors, blades or scrapers rotating with said shaft

above said floors, and rotary screw-conveyers arranged below said floors for delivering material discharged from one floor to the center of the floor below, substantially as and for the 5 purpose specified.

5. The combination of an upright trunk or cylinder, A, hollow floors B B', having discharge-openings c, the hollow rotary shaft E, the steam jacketed compartment D, below the 10 floor B', and having discharge-chutes K, the hopper-boys G G' G², comprising perforated pipes g, projecting from said shaft, and blades or scrapers h, and the blower H, all substantially as specified.

6. The combination of the hollow rotary shaft E, and hopper-boys, each comprising perforated pipes g, and blades or scrapers h, cut or slit transversely, and having the outer ends of the portions between the slits bent or deflected, as described, so that said portions 15 stand at an angle to said pipes, substantially as specified.
